UNITED STATES PATENT OFFICE

119,775

DESIGN FOR A DOUGH ROUNDING MACHINE

Harold Van Doren, Toledo, Ohio, assignor to
Baker Perkins Inc., Saginaw, Mich., a corpora-
tion of New York

Application July 3, 1939, Serial No. 85,840

Term of patent 14 years

To all whom it may concern:

Be it known that I, Harold Van Doren, a citizen of the United States, residing at Toledo, Lucas County, State of Ohio, have invented a new, original, and ornamental Design for a Dough Rounding Machine, of which the following is a specification, reference being had to the accompanying drawing, forming a part thereof.

Figure 1 is a front view in perspective of a rounder showing my new design.

Figure 2 is a rear view of the same.

The essential feature of my invention resides in the head portion shown in full lines.

I claim:

The ornamental design for a dough rounding machine, as shown and described.

HAROLD VAN DOREN.
